UNITED STATES PATENT OFFICE

WARREN S. WATTS, OF LOUISVILLE, KENTUCKY, ASSIGNOR TO ESKIMO PIE CORPORATION, OF LOUISVILLE, KENTUCKY, A CORPORATION OF DELAWARE

VACUUM JAR PROTECTIVE DEVICE

Application filed October 24, 1928. Serial No. 314,656.

The present invention relates to a protective means intended for association with vacuum bottles and jars, and has to do particularly with an inner wall or cell for use with such a device when employed for refrigerated storage purposes.

With the advent of the now internationally known product "Eskimo pie", many innovations, particularly of a nature adapted to produce or preserve "Eskimo pies", came on to the market. Among these have been new devices for the preservation of this article in a refrigerated container.

The novelty and attractiveness of "Eskimo pie" has been such that there has been and there is now a demand for it which it is difficult to supply, not because ice cream manufacturers cannot manufacture sufficient of these articles of that quality which will satisfy the public taste, but because of the inefficient facilities heretofore employed for its marketing and preservation. This serious difficulty has most recently been overcome in the eastern part of the United States and elsewhere by an innovation, the subject matter of this application for Letters Patent, namely, the employment of a vacuum jar as a storage container for "Eskimo pie", such jar being from time to time supplied with an amount of solidified carbon dioxide in cake form or other evaporating refrigerants.

In New York particularly, tens of thousands of jars of the vacuum type with wide mouths especially for this purpose have been placed in retail establishments as silent advertisements for "Eskimo pie", and in these jars, along with a number of "Eskimo pies", there has been placed a block of solidified carbon dioxide, such carbon dioxide either being wrapped in paper or boxed, the covering thereover to retard evaporation. This means of storage has been devised to keep the "Eskimo pies" solidified, the internal temperature of the jars being probably 130 degrees below zero Fahrenheit. At this temperature, "Eskimo pie" is particularly delicious, and so far as is known, the only objection to the system of marketing followed has been an infrequent breakage of the glass cell of the vacuum jar due to rough handling

of the "Eskimo pies", to the too sudden escape of gaseous carbon dioxide upon removal of the jar cap and following its evaporation from cake form, and/or the too sudden rush of warm atmospheric air into the jar and against the walls of the container coincidental with the removal of the jar cap.

A simple device to overcome each and all of these difficulties has been devised and it comprises the subject matter of the present application.

As may be readily understood from the foregoing introductory description, the objects of the invention are to render more stable a vacuum storage jar, and to prevent, as far as is humanly possible, the destruction of the glass portion thereof because of rough handling, because of too sudden discharge of carbon dioxide gas therefrom, and/or because of a too sudden inrush of outside air against the inner walls of the jar.

These objects, and such other objects as may hereinafter appear, are obtained by the novel combination of elements herein described, their construction, and the manner of their arrangement one with another.

One embodiment of the invention is illustrated in the accompanying drawing, in which:

Figure 1 is a perspective view of a detachable and separable basket or liner which is adapted to be placed in a vacuum jar; and

Figure 2 is a longitudinal section through a vacuum storage jar in which such basket or liner is disposed.

Like reference characters are employed for indicating similar parts in the drawing and in the description of the invention hereinafter given.

The two figures in the drawing should be read conjointly. The vacuum jar is of a conventional structure but selected as to its dimensions to meet the requirements of "Eskimo pie" marketing. It is a wide mouthed jar and relatively shallow in proportion to its diameter.

The jar itself comprises a glass shell 10 having an inner wall 11 and an outer wall 12. The space 13 intermediate walls 11 and 12 is exhausted of air through a seal-off des-

gnated 14. The inner wall 11 terminates in a hemispherical bottom or one of any other selected configuration.

Upon the outer wall 12 of the shell 10 and near its top is a bead or peripheral rib 15 extending circumferentially about the shell 10. Disposed thereabove is an annular band or collar 16, generally of a non-conductor of heat and cold.

Resting upon the collar 16 is an annular member or ring 17 of greater thickness than collar 16, and to this latter is secured an external sleeve 18 with depending flanges the lowermost of which is beaded and is joined to the outer cylinder 19 by a threaded connection or by other suitable joinder. While the joinder between the cylinder 19 and the sleeve 18 may be other than a threaded connection, a threaded engagement facilitating assembly of the glass portion within the metal parts is highly desirable. This latter, cylinder 19, is closed at its bottom by a base 20 having a centrally disposed recess 21 therein, there being a spiral spring 22 disposed in said cup and engaging the shell 10 adjacent and about the seal-off 14.

Intermediate the cylinder 19 and the outer wall 12 of the shell 10 may be disposed a spacer or washer member 23, it being usual and customary to have the glass shell 10 come in contact with the enclosing metal casing only at the top of said shell 10. The less actual surface contact there is between such metal outer shell and the glass vacuum compartment the better insulation and the more successful is the operation of the device.

The base 20 may be supplied with legs 24 or it may be otherwise provided with means for vertical support, the whole device being maintained upright upon a stand, a showcase or other flat topped device for display.

Across the top of the shell 10 is a relatively flat truncated coniform cork 25. There is a metallic top 26 thereover having a flange 27 extending down about the periphery of the cork 25 a short distance for purposes of protection and for producing a more finished appearance. The cover 26 has a centrally disposed handle 28 secured thereto by fastening means 29 which may be of any desired character.

Within the jar or shell 10 is a metallic basket 30 having a rounded bottom 31. The basket and bottom may be formed of a single piece of material, or of several pieces of material joined together in any suitable manner. For neatness the basket has a finished top edge 32 as is clearly shown in Figure 1.

Basket 30 is of about the same diameter as the shell 10 and is disposed within the shell 10 as is shown in Figure 2 by frictional engagement with the walls of shell 10. The construction of the basket is such that it is somewhat flexible or compressible to lend it to following the contour of wall 11 and to

70 permit of it being maintained against accidental displacement therefrom. While in the drawing the basket 30 does not extend to the bottom of the shell 10, it is possible to provide without appreciable loss of efficiency a basket 30 which will exactly conform with the configuration of the shell 10. It is possible to form the basket as an integral part of the inner wall 11 of the shell 10 when so desired, but this of course prevents the removal of the metal part from the glass for ready cleansing. When so formed, a portion, the inner surfaces of the basket 30 should project from the glass wall of the vessel 10 for reasons hereinafter made apparent.

75 Within the basket 30 as illustrated is shown a plurality of "Eskimo pies" 33 of a general parallelopiped configuration and wrapped in their usual foil covering.

80 A block of carbon dioxide, generally wrapped or in a box, is placed within the jar when in use but this is not here shown.

85 As indicated, the refrigerant, is solidified carbon dioxide and the temperature thereof at the time of its conversion from the solidified or cake form into gas is about 135 degrees minus Fahrenheit. This is a very intense cold, and may sometimes have a tendency to render the glass shell 10 quite brittle.

90 As an incident to the chilling and refrigerating of air and the articles contained within the shell 10, there is an evaporation of solidified carbon dioxide which becomes gaseous carbon dioxide. There is sometimes an outward rush of such gas when the jar is opened after it has been closed for some time. This rush of gas is appreciable only when the jar has been sealed for quite some time and there has been a rather extensive evaporation of the solid carbon dioxide due to an exceptionally warm external atmosphere.

95 The glass of the shell 10 is always fragile and it has sometimes been injured by carelessly throwing "Eskimo pies" into the jar, and again the glass has been injured by the rough and unnecessarily vigorous or careless manner in which the jars are handled by dealers.

100 Very infrequently there has been a shattering of the glass of the shell 10 coincidental with the rush of atmospheric air into the shell 10, this occurring principally when the jar has been closed for a long time and has become very intensely cold.

105 The metal of the basket 30 has a higher heat conductivity than the glass of shell 10. The basket is not easily broken or distorted, and when placed within the jar as is shown in Figure 2 it provides a protective wall for the shell 10 preventing any possibility of damage to the shell 10 due to a careless handling of "Eskimo pies" in the jar or an improper removal of such articles therefrom. The basket 30 acts as a reinforcing member and prevents a too sudden expansion or contraction

of the wall 11 when internal pressure is removed therefrom or the wall 11 is exposed to conditions producing a marked heat fluctuation.

5 When the cork 25 is removed, and atmospheric air is allowed to enter the jar as it may do when the jar is held open for some time, such warm air, instead of coming directly into contact with the inner wall 11 is arrested by the metallic material of the basket 30 which, because of its high heat conductivity, absorbs quickly the heat of the atmospheric air and prevents such warm air from striking the perhaps brittle inner wall 11 of the shell 10.

10 The basket 30 also provides a means for maintaining a thin layer of air thereunder and not disturbed by the displacement of some of the air in the jar by atmospheric air 20 with the opening of the shell 11, hence, there is no sudden stress upon the material of the inner wall 11 even as an incident to a sudden change in temperature of the major portion of the air within the jar incident to extended 25 opening of jar 10. In order to prevent too great a displacement of air from the jar at any time, the basket 30 is made shorter than the shell 10 to permit of the retention of a considerable volume of chilled air at all times 30 between the basket 30 and wall 11 at the bottom of the jar.

The basket in the form illustrated is readily removable in order that both it and the jar may be cleansed.

35 I claim:

1. An internal protective member for vacuum jars comprising a shell of foraminous material of high heat conductivity and frictionally engaging the inner wall of said jar.
2. A protective member for vacuum jars comprising a shell of flexible and compressible material of high heat conductivity frictionally engaging the inner wall of said jar.
3. A protective member for vacuum jars comprising a shell of foraminous material of high heat conductivity frictionally engaging the inner wall of said jar and spaced from the bottom thereof.
4. The combination with a vacuum jar used 50 for refrigerated storage purposes and normally containing an evaporating refrigerant, of a basket of substantially the same contour as the inner wall of such vacuum jar and of relatively closely meshed metallic material 55 adapted to frictionally engage the wall of such vacuum jar.

WARREN S. WATTS.
